DESIGN FOR A DISPLAY RACK

John R. Kneebone, Western Springs, Ill., assignor to Tested Papers of America, Inc., Chicago, Ill.,
a corporation of Ohio

Application August 30, 1940, Serial No. 94,728

Term of patent 7 years

To all whom it may concern:

Be it known that I, John R. Kneebone, a citizen of the United States, residing at Western Springs, in the county of Cook and State of Illinois, have invented a new, original, and ornamental Design for Display Racks, of which the following is a specification, reference being had to the accompanying drawing, forming part thereof.

The figure of the drawing is a perspective view of a display rack, showing my new design.

I claim:

The ornamental design for a display rack, as shown.

JOHN R. KNEEBONE.
